UNITED STATES PATENT OFFICE.

LAUREN S. BEARDSLEY, OF NAUGATUCK, CONNECTICUT.

DESIGN FOR AN INSULATOR-BRACKET.

SPECIFICATION forming part of **Design No. 25,178, dated February 18, 1896.**

Application filed December 20, 1895. Serial No. 572,795. Term of patent 14 years.

To all whom it may concern:

Be it known that I, LAUREN S. BEARDSLEY, a citizen of the United States, residing at Naugatuck, in the county of New Haven, State of Connecticut, have invented and produced a new and original Design for Insulator-Brackets, of which the following is a specification, reference being had to the accompanying drawing, forming a part of this specification.

The design consists of an insulator-holder having three upright prongs provided on their upper portions with spirally-formed ridges, the central prong or pin being provided below the spirally-formed portions with an opening, the remaining pins joining to a base through a bend or curve, all the said parts being cir-

cular in cross-section and formed of an integral piece of material.

In the accompanying drawing, which is a vertical elevation of the holder embodying my design, I have illustrated the invention as above set forth.

What I claim, and desire to secure by Letters Patent, is—

The design for an insulator-holder substantially as shown and described.

In testimony whereof I affix my signature in the presence of two witnesses.

LAUREN S. BEARDSLEY.
